(57) **CLAIM**

We claim the ornamental design for a charger for electric vehicle, as shown and described.

DESCRIPTION

FIG. 1 is a front, right and top perspective view of a charger for electric vehicle showing our new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of an encircled portion 9 of FIG. 1.

The dot-dash broken line portion of the figure drawings is included to show boundaries of enlarged views that form no part of the claimed design.

The broken lines depict portions of the charger for electric vehicle in which the design is embodied that form no part of the claimed design.
